UNITED STATES PATENT OFFICE.

JAMES J. HERVEY, OF RANDSBURG, CALIFORNIA.

CYANID-TANK.

SPECIFICATION forming part of Letters Patent No. 698,016, dated April 22, 1902.

Application filed November 23, 1901. Serial No. 83,405. (No model.)

To all whom it may concern:

Be it known that I, JAMES J. HERVEY, a citizen of the United States, residing at Randsburg, in the county of Kern and State 5 of California, have invented a new and useful Cyanid-Tank, of which the following is a specification.

This invention relates generally to tanks employed in treating ores with cyanid solutions, and more particularly to a tank whereby water and air or gas may be injected into the tank at the time the material is being subjected to the action of the cyanid solution.

The object of the invention is to provide a 15 tank whereby the operation of the solution is facilitated.

The invention consists in the novel features of construction and combination hereinafter fully described, and pointed out in the claims.

20 In the drawings forming part of this specification, Figure 1 is a sectional elevation illustrating the practical application of my invention.

Fig. 2 is a horizontal sectional view of the tank, taken on the line 2 2 of Fig. 1; and 25 Fig. 3 is a horizontal sectional view taken on the line 3 3 of Fig. 1.

In carrying out my invention I employ a cylindrical tank A, which is preferably constructed of wood and is supported upon a 30 suitable base or platform B.

C indicates a tapering circular ring or plate arranged at the bottom of the tank, said ring or plate resting upon the flat circular plate D and which is bolted to the base or platform B, 35 and connected also to this circular plate D is the central circular cone E, said circular cone E and tapering plate C constituting the bottom of the tank. Within the tank is arranged a metallic annular lining F, said annular 40 lining extending substantially parallel to the sides of the tank and also to the tapering plate C. This lining does not extend entirely to the top of the tank A, but does extend some distance above the middle line of the

45 same. The circular lining-space is divided into a series of vertical compartments by means of the vertical partitions G. An annular pipe H surrounds the tapering plate C and communicates with the tank at regular 50 intervals, as shown at I, a valve being arranged at each point of connection, so that communication can be established or cut off

between the circular pipe and any particular compartment of the annular lining. A hot-air pipe H' communicates with the annular 55 pipe H at one side, and a cold-air pipe H² communicates with the said pipe at the opposite side.

K indicates a main water-supply pipe having vertical branch pipes K' and K², from 60 which lead horizontal branch pipes K³, said branch pipes K³ leading into the tank-lining at the upper end thereof, it being understood that there are as many water-pipes K³ as there are compartments of the lining. 65

L indicates a pipe which leads from some other tank or other suitable source of supply, said pipe extending into the tank at its upper end, and, if desired, this pipe may be connected to the vertical branch pipe K', it being understood 70 that the main pipe and all the branch pipes are provided with suitable valves, so that any particular portion can be cut off when necessary.

M indicates a vertical pipe extending upwardly from the main pipe K through the apex of the central cone E. 75

N indicates a pipe extending into the bottom of the tank into the V-shaped trough formed by the juncture of the central cone E 80 and the tapering plate C, and O designates a similar pipe leading from the bottom of the tank at the opposite side, said pipes N and O being intended to be used for charging and discharging the tank, said pipes being connected by means of pipes P, which in turn are connected to a charging-pump Q. 85

R indicates a pump connected to the hot-air pipe H' for the purpose of forcing hot air into the annular pipe H. 90

The lining F does not extend entirely to the bottom of the tank, as most clearly shown in Fig. 1, and a filtering-screen S connects the lower end of the jacket and the sloping sides of the central cone E, thereby preventing the 95 pipes N and O becoming clogged.

By means of an apparatus constructed as herein shown and described I am enabled to economically treat auriferous material at any stage of its conversion by means of the cyanid process, and by having the annular lining open at the bottom only and having air and water pipes leading thereinto the mass to be treated will be sufficiently agitated to

bring the cyanid solution into contact with the gold-bearing material, thereby producing the best possible results.

Having thus fully described my invention, 5 what I claim as new, and desire to secure by Letters Patent of the United States, is—

1. A tank having an annular lining open at the bottom, said lining having air and water pipes leading thereto, substantially as de- 10 scribed.

2. A cyanid-tank having an annular lining open at the bottom said lining being divided into a series of compartments, each compartment having an air and a water tank com- 15 municating therewith, substantially as de- scribed.

3. A cyanid-tank having a tapering bottom and the central cone arranged in connection with the said tapering bottom, the annular

lining arranged upon the interior of the tank 20 and having air and water pipes connected thereto, and the charging and discharging pipes leading to and from the bottom of the tank, substantially as described.

4. Cyanid-tank having a tapering bottom 25 and a central cone arranged in connection with the bottom, an annular lining arranged in the tank and open at its lower end, a filtering - screen connecting the lower end of the lining and the central cone, the air and 30 water pipes, the charging and discharging pipes, and the forcing means connected with said pipes, substantially as set forth.

JAMES J. HERVEY.
